UNITED STATES PATENT OFFICE

112,487

DESIGN FOR AN AUTOMOBILE TOP AERIAL

Thomas J. Prentice, Piedmont, Calif.

Application September 20, 1938, Serial No. 80,008

Term of patent 7 years

To all whom it may concern:

Be it known that I, Thomas J. Prentice, a citizen of the United States, residing at Piedmont, in the county of Alameda and State of California, have invented a new, original, and ornamental Design for an Automobile Top Aerial, of which the following is a specification, reference being had to the accompanying drawing, forming part thereof.

Figure 1 is a view in perspective of an automobile top aerial showing my new design;

Figure 2 is a view in rear elevation.

I claim:

The ornamental design for an automobile top aerial, as shown.

THOMAS J. PRENTICE.
